UNITED STATES PATENT OFFICE.

TULLY R. CORNICK, OF PETALUMA, CALIFORNIA.

AUTOMOBILE LOCK SYSTEM.

Application filed May 13, 1921. Serial No. 469,304.

To all whom it may concern:

Be it known that I, TULLY R. CORNICK, residing at Petaluma, in the county of Sonoma and State of California, a citizen 5 of the United States, have invented certain new and useful Improvements in Automobile Lock Systems, of which the following is a specification.

This invention relates to a locking apparatus for fuel feed systems of automobiles.

The primary object of the invention is the provision of a locking means suitable for use for either gravity, pressure or vacuum feed systems.

15 A further object is to provide means for draining the vacuum tank when the main system has been cut off to prevent the use of the fuel in the gravity compartment of the vacuum tank.

20 A further object is to arrange in the vacuum system an auxiliary tank in the main feed line, which will feed by gravity a given amount of fuel to the vacuum tank for initial starting purposes, where, for instance, the carburetor may have been drained by an attempt to start the car when the main feed line is locked.

25 A further object of the invention is to provide a system which, while it is effectually locked against theft, will, however, permit of a slight movement of the car when it is desirable perhaps to move the car a moderate distance in case of fire.

In the accompanying drawings:

30 Fig. 1 is a diagrammatic view showing my invention as applied to the vacuum system;

Fig. 2 is an enlarged view, partly in section, of the auxiliary supply tank;

40 Fig. 3 is a view of the dash, disclosing the manner of locking the controlling valve of the auxiliary tank;

Fig. 4 is a vertical section through the drainage tank;

45 Fig. 5 is a top plan view thereof;

Fig. 6 is a detail view of the valve-actuating and locking lever.

As indicated in Fig. 1, the usual vacuum system comprises a supply tank 1, a vacuum tank 2, and a carburetor 3, the fuel being fed from the supply tank to the vacuum tank through the action of the vacuum produced by the engine. It is understood that when a certain amount of fuel is drained into the upper half of the vacuum tank 2, the vacuum ceases to operate, through a float,

and until the level of the fuel in said tank reaches a certain lower level, it feeds the carburetor by gravity alone. When this certain lower level is reached, the vacuum 60 is again operated until the original higher level is again reached, whereupon the operation is repeated.

The numeral 4 indicates an auxiliary tank arranged in the supply line, at a higher elevation than the vacuum tank 2, being connected by a feed-pipe 5 to the supply tank 1. Arranged within the auxiliary tank is a standpipe 6, extending well up into the tank, thereby at all times leaving the tank partially filled with fuel, for a purpose herein-after set forth.

A rotary valve is arranged directly below the auxiliary supply tank, having an inlet port 7 connected to the standpipe 6, and an 65 outlet port 8, said ports being controlled by a rotary plug valve 9 having a transverse duct 10 which is adapted to communicate with the inlet and outlet ports 7 and 8 when in certain position. The outlet port is connected by feed pipe 11 to the upper part of the vacuum tank 2, which in turn is connected on the bottom by feed pipe 12 to the carburetor 3, thus completing the feed line 70 between the main supply tank 1 and the carburetor 3.

The valve stem 13 of the valve 9 is adapted to extend through the dash of the car, where it may be conveniently actuated by the operator. When the stem is turned 80 to the position which cuts off communication between the auxiliary tank and the feed-pipe 11, an arm 14 provided with an opening 15 is adapted to assume a horizontal position, the opening 15 therein registering 85 with the bolt 16 of the lock 17, in this manner preventing the unauthorized use of the car.

In view of the fact that the vacuum tank 2 always holds sufficient gas to allow the car 100 to operate for some miles, it becomes necessary not only to close the gasoline line from the main supply tank 1, but it is desirable to remove all of the gasoline from the vacuum tank. To effect this, a branch or drainage 105 tank 18 is arranged at an elevation sufficiently lower than the vacuum tank to allow the gasoline in the vacuum tank to drain into the drainage tank, being connected thereto by feed pipe 19, the end thereof extending into the drainage tank and downwardly as at 20, very close to the bottom,

thus effecting the sealing of the pipe 20 when the vacuum tank is drained. It is desirable to draw from the drainage tank the contents thereof as the engine is again started, 5 in order that it may properly function each and every time the engine is stopped. For this purpose, I have preferably provided a tank with a syphoning or suction tube 21, which extends from the bottom of the tank 10 to the top, and in turn is connected to the feed-pipe 5 arranged between the main supply tank and the auxiliary supply tank 4. In this manner, I obtain the full effect of the 15 gasoline which has the effect of drawing off what gasoline may have entered the drainage tank from the vacuum tank.

Obviously, when running, it is necessary to have the drainage tank so connected with 20 the main feed line and the vacuum tank that the gasoline will not flow from either point into the drainage tank. For this purpose I have preferably extended the feed pipe 19 into the drainage tank and down- 25 wardly as at 20 and very close to the bottom. The drainage tube extending from very close to the bottom of the tank upward and after having made one coil (thereby prohibiting the passage of air up- 30 ward and through said pipe) passes through the top of the tank, where it is connected to the main feed pipe 5, arranged between the main supply tank and the auxiliary tank 4. I arrange in the upper part thereof a re- 35 ciprocating valve 24 normally held closed by the spring 25 against the valve seat 26. In this manner, with the reciprocating valve 24 in its normally closed position, the drainage tank becomes sealed or locked as soon as 40 the open ends of the feed and drainage pipe ends are covered with gasoline.

In order to remove the gasoline from the vacuum to the drainage tank, it is necessary to open the reciprocating air valve 24. This 45 action, however, not only breaks the seal to pipe 20 leading to the vacuum but also to that of the coil pipe leading to the main supply tank. It is therefore necessary to close the main feed pipe line 5 when air 50 valve 24 is opened. I have therefore preferably placed a cut-off valve 21' in feed line 5 just behind the point where the drainage coil connects with feed line and between this tank 18 and the main supply tank 1.

55 Cut-off valve 21' is preferably actuated by a push rod 22, extending through the floor board, being provided with a notch 23 which engages a projection (not shown), serving to hold the valve closed against the 60 tension of the spring 22' when in position to drain the vacuum. An arm 27 attached to the valve 21' is adapted to automatically open the reciprocating air valve 24 when the cut-off valve 21' is closed or turned to a 65 position to cut off the main supply tank 1.

When running, the normal position of valve 24 is closed, while 21 is opened. When draining the vacuum tank, valve 24 is open and valve 21' is closed. Also when draining the drainage tank, valve 24 is open and valve 21' is closed. The only difference being that while the vacuum tank is being drained, valve 9 is closed and held fast by the locking arrangement; while when the drainage tank is being drained and the vacuum filled, 70 the engine is running and valve 9 is opened. Therefore, with the engine running, valve 9 open, and valve 24 open, allowing air to enter the drainage tank, and valve 21' closed, thereby cutting off the main supply 75 tank 1, it will be noted that the full effect of the suction is exerted upon draining the drainage tank. The action of the suction being so much more rapid than the gravity flow from the bottom of the vacuum tank 80 through feed pipe 19, the drainage tank is immediately drained, even though the same fuel is returning from the vacuum to the drainage tank through feed pipe 19. As soon as the engine has made several revolutions and the suction started working, 85 push rod 22 is actuated by the foot. A slight pressure on rod 22 releases the notch 23 from the projection, which allows the spring (22') to force the rod 22 up, thereby opening valve 21', leading to the main supply tank 1. This action of valve 21' has caused the arm 27 thereto attached to be raised, which in turn releases the pressure on spring 25 of reciprocating valve 24, thereby allowing the valve 24 to close. 90

Ordinarily there is sufficient fuel in the carburetor to start the engine, after which the supply is taken from the vacuum tank 2. If, however, some unauthorized person 105 should attempt to start the engine, thereby using up the fuel in the carburetor, the operator would have difficulty in starting, inasmuch as the vacuum tank has been drained. To overcome this, I preferably arrange an outlet 28 in the bottom of the auxiliary tank 4, which leads to the casing of the valve 9. The valve 9 is provided with an additional duct 29' which is arranged at 110 an angle to the transverse duct 10, the duct 29 being of such relation to the duct 10 as to cause the outlet 28 to register with the feed-pipe 11 when the valve is turned in that position. This causes the contents of the auxiliary tank 4 to drain by gravity to the 115 vacuum tank 2, giving a sufficient supply of fuel to start the engine. To facilitate the draining of this tank, I preferably provide an air vent 30 leading from the top of the tank to a port 31 in the casing of the valve 29. In the casing of the valve 9, I also provide a comparatively small air-port 32, which, when the valve is turned in such a 120 position as to drain the tank 4, is caused to register with the air-vent 30 by means of 125

128

a recess 33 in the valve 9, this arrangement eliminating any possibility of the auxiliary tank not supplying the fuel rapidly enough to the vacuum tank 2.

5 In the vacuum system, the operation is as follows: In bringing the car to a stop, the operator steps upon the push-rod 22, thereby moving the valve 21' to such a position as to close the feed line system and open the 10 air-valve 24 within the drainage tank 2, thus permitting the vacuum tank to drain into the drainage tank, after which the valve 9 is turned to such a position as to discontinue communication between the auxiliary tank 15 4 and the feed-pipe 11, the valve being held and locked in this position by means of the locking bolt 16 engaging the opening 15 in the arm 14, which in turn is attached to the valve 9.

20 Upon starting up the car, valve 9 is unlocked and turned to a position to establish communication through the stand pipe 6 in auxiliary tank 4 and the main feed line 11, thence through feed pipe 11 to the vacuum tank. The engine being provided with sufficient fuel for starting, by the contents of the carburetor, whereupon the drainage tank is emptied. The push rod 22 is now released, closing the air valve 24 and opening the 25 30 valve 21', establishing communication between the main supply tank and the feed line and the vacuum tank 2. The starting of the engine produces sufficient vacuum to start the circulation of fuel through the engine system. Should the operator in starting discover that an attempt has been made to start the motor, and the carburetor exhausted of its supply, the valve 9 is then turned to such a position as to establish communication with the outlet 28 in the bottom 35 40 45 of the auxiliary supply tank 4, whereupon the contents thereof (in that the tank has been vented through pipe 30) is delivered to the feed-pipe 11, thence to the vacuum tank 2, and to the carburetor 3 by gravity, giving a sufficient charge to start the engine, after which the usual system is brought into operation.

I claim:

50 1. A fuel feeding system comprising a main supply tank, a carburetor, a vacuum tank interposed between the carburetor and the main supply tank, a drainage tank connected to the vacuum tank, said drainage 55 tank being in communication with the vacuum feed line, a valve interposed between the vacuum tank and the main supply tank to cut off communication therebetween and to permit passage of fuel from the drainage tank to the vacuum tank, and means for locking the valve.

60 2. A fuel feeding system including a main supply tank, a vacuum tank, and a carburetor, a feed-line extending between them, a drainage tank in connection with said vac-

uum tank, means for draining the fuel from the vacuum tank into the drainage tank, said means including an air vent and a valve in the feed line between the main supply and vacuum tanks.

70 3. A fuel feeding system including a main supply tank, a carburetor and a vacuum tank, a drainage tank having communication with said vacuum tank, and a feed line extending from the main supply tank, the drainage tank and the vacuum tank, means for draining fuel from the vacuum tank to the drainage tank including an air vent in said drainage tank and means for feeding fuel from said drainage tank to the vacuum tank, including a valve interposed between the main supply tank and the drainage tank.

75 80 85 90 95 4. A fuel feeding system including a main supply tank, a carburetor and a vacuum tank, a drainage tank having communication with said vacuum tank, and a feed line extending from the main supply tank, the drainage tank and the vacuum tank, means for draining fuel from the vacuum tank to the drainage tank including an air vent in said drainage tank, means for feeding fuel from said drainage tank to the vacuum tank including a valve interposed between the main supply tank and the drainage tank, and an auxiliary tank in said feed line normally maintaining a reserve supply of fuel and provided with means to cut off the normal passage of fuel through the auxiliary tank.

100 105 110 115 5. A fuel feeding system including a main supply tank, a carburetor and a vacuum tank, a drainage tank having communication with said vacuum tank, and a feed line extending from the main supply tank, the drainage tank and the vacuum tank, means for draining fuel from the vacuum tank to the drainage tank including an air vent in said drainage tank, and means for feeding fuel from said drainage tank to the vacuum tank including a valve interposed between the main supply tank and the drainage tank, an auxiliary tank in said feed line normally maintaining a reserve supply of fuel and provided with means to cut off the normal passage of fuel through the auxiliary tank, and means for draining the reserve supply of fuel from said auxiliary tank to the vacuum tank.

120 125 130 6. A fuel feeding system comprising a main supply tank, a carburetor, a fuel feed line therebetween, a vacuum tank interposed in said line, a drainage tank arranged on a lower level than the vacuum tank and communicating with the lower end thereof, a valve arranged on the top of said drainage tank in communication with the main feed line, an air vent arranged in said drainage tank, actuating means for simultaneously closing said valve in the feed line and opening said air vent whereby with the lock

valve interposed between the auxiliary tank and the vacuum tank closed, the contents of the vacuum tank will be received in the drain tank and with the lock valve open and 5 the engine running, the contents will be drawn back into the vacuum tank, when the actuating means is in one position, said actuating means when moved to the opposite direction adapted to close said air vent and 10 establish communication between the main supply tank and the main feed line.

7. A fuel feeding system including a main supply tank, a carburetor and a vacuum tank, a drainage tank having communication 15 with said vacuum tank, and a feed line extending from the main supply tank, the drainage tank and the vacuum tank, means for draining fuel from the vacuum tank to the drainage tank including an air vent in 20 said drainage tank, means for feeding fuel from said drainage tank to the vacuum tank including a valve interposed between the main supply tank and the drainage tank, an auxiliary tank in said feed line normally 25 maintaining a reserve supply of fuel and provided with means to cut off the normal passage of fuel through the auxiliary tank, means for draining the reserve supply of fuel from said auxiliary tank to the vacuum 30 tank, said means including a duct connected with the bottom of the auxiliary tank, and an air vent in the top thereof, and means connecting the duct with the feed-line to the vacuum tank and the air vent with the atmosphere. 35

8. A fuel feeding system including a main supply tank, a carburetor, and a vacuum tank, a drainage tank and connection between the bottom of the vacuum tank and 40 the drainage tank, including an open-ended pipe terminating close to the bottom of the drainage tank, a feed-line extending from the main supply tank to the drainage tank and to the vacuum tank, a drainage

open-ended tube extending into the drainage tank and terminating close to the bottom thereof, and connected with said feed-line, a valve interposed in the feed-line between the drainage tube and the main supply tank, the whole so arranged that the fuel from the 45 vacuum tank can be drained into the drainage tank, and upon the vacuum tank being subjected to suction the valve may be operated to permit the drainage fuel in the drainage tank again to be delivered to the 50 vacuum tank. 55

9. A fuel feeding system including a main supply tank, a carburetor, and a vacuum tank, a drainage tank and connection between the bottom of the vacuum tank and 60 the drainage tank, including an open-ended pipe terminating close to the bottom of the drainage tank, a feed-line extending from the main supply tank to the drainage tank and to the vacuum tank, a drainage open-ended tube extending into the drainage tank and terminating close to the bottom thereof, and connected with said feed-line, a valve interposed in the feed-line between the drainage tube and the main supply tank, 65 the whole so arranged that the fuel from the vacuum tank can be drained into the drainage tank, and upon the vacuum tank being subjected to suction the valve may be operated to permit the drainage fuel in the 70 drainage tank again to be delivered to the vacuum tank, an air valve mounted in said drainage tank to permit the escape of air from the drainage tank as the vacuum tank is drained thereinto, and to break the liquid 75 seal normally existing at the open ends of the tubes extending into said drainage tank, and means for actuating said air valve and said valve simultaneously. 80

In testimony whereof I hereunto affix my 85 signature.

TULLY R. CORNICK.
